(57) **CLAIM**

The ornamental design for an IC memory card, as shown and described as shown.

DESCRIPTION

FIG. 1 is a perspective view of the first embodiment of an IC memory card showing our new design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof;

FIG. 7 is a bottom plan view thereof;

FIG. 8 is a perspective view of a second embodiment of the IC memory card;

FIG. 9 is a front elevational view of FIG. 8;

FIG. 10 is a rear elevational view of FIG. 8;

FIG. 11 is a left side elevational view of FIG. 8;

FIG. 12 is a right side elevational view of FIG. 8;

FIG. 13 is a top plan view of FIG. 8; and,

FIG. 14 is a bottom plan view of FIG. 8.

The details shown in broken lines in FIGS. 1, 2, 8 and 9 are for illustrative purposes only and form no part of the claimed design.
